LIQUID FUEL BURNERS

Harold E. Jackson, Plympton, Devon, and Douglas Raymond Dean, Plymouth, Devon, England, assignors to Tecalemit (Developments) Limited, Plymouth, Devon, England

Filed Feb. 23, 1965, Ser. No. 434,493
8 Claims. (Cl. 158—28)

This invention relates to liquid fuel burners and it has for its principal object the provision of improvements in oil fuel burners, although it is also applicable to burners intended for use with other liquid fuels.

A further object of the invention is the provision of an oil or other liquid fuel burner which will operate at high efficiency with a blue flame and which will produce a low content of carbon monoxide in the waste products.

The invention, in one of its aspects, accordingly provides a liquid fuel burner comprising a combustion chamber having a supply passage opening into it and means including an atomising head and nozzle for injecting fuel and primary combustion air into the supply passage and through it into the combustion chamber in a direction to cause burning fuel and air to circulate in this chamber, which chamber includes at least one inlet for secondary air to complete combustion and an outlet for the discharge of burning gases, the arrangement being such that liquid fuel and primary air in a quantity insufficient for complete combustion can be injected into the supply passage at a speed sufficient to prevent combustion adjacent the nozzle.

The combustion chamber is preferably made of a generally circular cross-section and has the supply passage opening into it in a tangential direction. The outlet for burning gases from the chamber is advantageously through perforations formed in a plate, which plate may be in the form of a removable cover for the top of the combustion chamber.

The fuel and primary air are preferably injected into the supply passage at an acute angle to the axis of the latter, in a direction which is inclined towards the centre of the combustion chamber and which is preferably also inclined downwardly towards the bottom of the combustion chamber. Furthermore, a deflector plate is preferably provided within the combustion chamber, which plate extends inwardly in an arcuate direction from a point which is located adjacent the inner end of the supply passage and adjacent the outer wall of the combustion chamber, the inner end of this deflector plate being located at an intermediate point between the wall and the centre of the combustion chamber. The upper edge of the deflector plate may be and preferably is spaced from the top of the combustion chamber, to allow the passage of burning gases over it, this edge being preferably inclined downwardly from the outer towards the inner end of the plate.

The secondary air is preferably admitted and drawn into the combustion chamber through an inlet which projects into the interior of the chamber and which is itself of a tapered form having its larger end within the chamber.

Further features of the invention will become apparent from the following description of a preferred form of oil fuel burner which exemplifies the invention. Reference will be made to the accompanying drawings, in which:

FIGURE 1 is a plan view of the burner, which is shown partly broken away and in section;

FIGURE 2 is a section taken on the line and in the direction indicated by the arrows Z—Z in FIGURE 1.

2

FIGURE 3 is a section taken on the same line but in a reverse direction, as indicated by the arrows Y—Y in FIGURE 1;

FIGURE 4 is a section taken on the line and in the direction indicated by the arrows Z—Z in FIGURE 1.

Referring to the drawings, the burner comprises an atomising head, indicated generally at 1, which is connected with a combustion chamber 2 by means of a base 3, which base, together with feet 4 mounted on the bottom of the chamber 2, supports the burner as a whole.

The atomising head 1 comprises an electric motor 5 which drives a centrifugal fan 6 and an oil pump 7. These together inject oil and primary air into a supply passage 8 leading into the combustion chamber 2. The oil is injected into this passage 8 through an atomising nozzle 9, whilst primary air is discharged through a draught tube 10 which surrounds the nozzle 9 concentrically with the latter.

As will be seen from the drawing the supply passage 8 leads into the cylindrical combustion chamber 2 in a generally tangential direction, whilst the nozzle 9 and draught tube 10 are inclined both inwardly (relatively to the axis of the passage 8) towards the centre of the chamber 2 and downwardly towards the bottom thereof.

Furthermore, in order to direct the gases entering and circulating in the combustion chamber, a deflector plate or baffle 11 is provided within the chamber, which plate is of arcuate shape, when viewed in plan, and extends into the chamber 2 towards the centre of the latter from a point where the side of the supply passage 8 meets the peripheral wall of the chamber. As will be seen from FIGURE 3, the top of the deflector plate 11 is spaced from the top of the combustion chamber 2 and is inclined downwardly towards its inner end.

The combustion chamber 2 is provided with a pair of spark electrodes 12 to ignite the gases whilst it also includes an inlet 13 for secondary air, the construction and operation of which will be more fully described.

A cover 14, which is formed with perforations 15 over substantially its whole area, is fitted to the top of the chamber 2 and the burning gases are discharged through these perforations, where they form a blue flame.

During working the pump 7 delivers oil at a high pressure to the nozzle 9, where the oil is atomised by being forced through a small orifice in the nozzle. At the same time primary air is delivered from the fan 6 through the draught tube 10. This air and the atomised oil are discharged together through the passage 8 into the combustion chamber 2.

The parts are so designed that the primary air delivered by the fan 6, in relation to the oil delivered by the pump 7, is insufficient to provide complete combustion of the oil. Furthermore, the oil and air are delivered at such a high velocity that the flame would be unstable if it were burning freely in the normal way. With the arrangement described, however, in which a reduced amount of primary air is introduced at high velocity to the atomised fuel leaving the nozzle 9, a very intimate mixture of the fuel and air can be obtained within the supply passage 8 while at the same time combustion near the nozzle 9 and within this passage is prevented.

Ignition of the burner is effected by the spark electrodes 12, which are connected to a high voltage means transformer (not shown). It is a feature of this burner that the ignition electrode can be mounted well clear of the main jet stream from the nozzle, so that they do not become over-heated during normal running of the burner, nor do they interfere with the flow of gases round the combustion chamber 2.

The discharge across the electrodes 12 to ignite the burner has only to be maintained for a few seconds, after which the ignition is switched off.

The angle of the discharge from the nozzle 9 and draught tube 10 and the angle and shape of the deflector plate or baffle 11 are so designed that the oil and gases do not strike the deflector plate too squarely but are deflected smoothly round the combustion chamber. Furthermore, by the time the jet of oil and air has reached the plate 11 it has been heated sufficiently by the flame for the oil not yet burnt to become gasified, which prevents droplets of oil from impinging and collecting on the plate 11.

As the stream of burning oil and air circulates round the combustion chamber 2 it passes over and round the secondary air inlet 13, where it causes secondary air to be drawn into the chamber; this secondary air mixes with the burning oil and primary air and causes true and complete combustion to start.

Experiments have shown that if the secondary air is simply allowed to enter through a plain hole in the bottom of the combustion chamber 2 the lower edge of the gas stream passing the secondary air inlet will burn too fiercely, with the production of flame noise. However, by both raising and spreading the secondary air supply so that it meets and is distributed in the stream of gases nearer the centre of the latter, the flame noise can be very greatly reduced or even eliminated. In the construction shown this is done by making the secondary air inlet in the form of a frusto-conical tube the upper end of which is the larger, as shown.

The amount of secondary air which is drawn in can be controlled by suitable designing of the size of the hole 16 in the bottom of the chamber 2 through which the secondary air enters.

The conical shape of the secondary air inlet 13 has been found to give a good spreading of the secondary air entering the combustion chamber 2, without offering too much resistance to the smooth progress of the burning gases round the chamber.

The burning gases circulate round the combustion chamber 2, after leaving the secondary air inlet 13, but they will now tend to rise towards the top of the chamber where they are partly reduced by the effect of the perforations in the cover 14. Small amounts of the burning gases escape through the individual perforations, the remainder of the gases continuing to circulate just below the cover plate 14 where some of them may pass over the passage 8 and deflector plate 11, the result being the formation of a continuous blanket of burning gases just below the cover plate 14.

All these gases will eventually be discharged through the perforations 15, where they will come into contact with external air, producing a blue flame with very good combustion characteristics.

If desired, a flame spreader, such as that indicated at 17 in FIGURE 3, may be fitted over the top of the cover 14. It has been found that such a flame spreader like any obstructions outside the combustion chamber has little effect on the flame characteristics.

The burner which has been described may be made of any suitable materials. The perforated cover plate 14 must be made of a flame-resistant material, such as a heat-resistant stainless steel, but other and cheaper materials can be used for the remainder of the combustion chamber 2. The walls of the latter could, for example, be made of mild steel sheet or of cast iron.

We claim:

1. A liquid fuel burner comprising a combustion chamber having a supply passage opening into it and means including an atomizing head and nozzle for injecting fuel and primary combustion air into said supply passage and through it into said combustion chamber in a direction to cause burning fuel and air to circulate in

said chamber, which chamber includes at least one inlet for secondary air to complete combustion and an outlet for the discharge of burning gas such that liquid fuel and primary air in a quantity insufficient for complete combustion can be injected into said supply passage at a speed sufficient to prevent combustion adjacent said nozzle, and a deflector plate within said combustion chamber extending inwardly in an arcuate direction with the concave side thereof toward the inside of said combustion chamber and extending from a point adjacent the inner end of said supply passage and adjacent the outer wall of said combustion chamber and having its inner end spaced between said wall and the center of said chamber, the upper edge of said deflector plate being spaced from the top of the combustion chamber and inclined downwardly from its outer end to its inner end, said inlet for secondary air projecting into the interior of the combustion chamber and being tapered having its larger end within said chamber and being positioned tangentially spaced from the end of said deflector plate so that the stream of gases is directed by said deflector plate over and around said secondary air inlet.

2. A liquid fuel burner comprising a combustion chamber of generally circular cross-section having a supply passage opening into it in a generally tangential direction, and means including an atomizing head and nozzle for injecting fuel and primary combustion air into the supply passage and through it into the combustion chamber to cause burning fuel and air to circulate in this chamber, wherein the combustion chamber is provided with a deflector in the form of a plate which extends inwardly in an arcuate direction, the convex side of said plate being positioned outwardly toward the wall of said combustion chamber, said deflector plate extending from a point adjacent the inner tangential end of said supply passage generally tangentially and adjacent the outer wall of the combustion chamber and which has its inner end spaced between this wall and the center of the chamber.

3. A burner as set forth in claim 2 above wherein the upper edge of the deflector plate is spaced from the top of the combustion chamber and is inclined downwardly from its outer end towards its inner end.

4. A burner according to claim 3 above wherein the outlets for the burning gases are provided by perforations in a cover plate which is fitted to the top of the combustion chamber.

5. A liquid fuel burner comprising a combustion chamber of generally circular cross-section having a supply passage opening into it in a generally tangential direction, an atomizing head and nozzle for injecting fuel and primary combustion air into the supply passage and through it into the combustion chamber to cause burning fuel and air to circulate in this chamber, said atomizing head and nozzle being at an acute angle to the axis of said supply passage in a direction which is inclined toward the center of the combustion chamber, said combustion chamber being provided with a deflector for deflecting the burning fuel and air inwardly from the wall of the chamber, at least one inlet for admitting secondary air into the chamber and a top having a plurality of outlets through it for the discharge of burning gases from the chamber.

6. A burner according to claim 5 above wherein said atomizing head and nozzle are further inclined downwardly toward the bottom of the passage and toward the bottom of said combustion chamber.

7. A liquid fuel burner comprising a combustion chamber of generally circular cross-section having a supply passage opening into it in a generally tangential direction, and means including an atomizing head and nozzle for injecting fuel and primary combustion air into the supply passage and through it into the combustion chamber to cause burning fuel and air to circulate in this chamber, said combustion chamber being provided with a deflector for deflecting the burning fuel and air inward-

ly from the wall of the chamber, at least one inlet for admitting secondary air into the chamber and projecting into the interior of the combustion chamber and being of tapered form having its larger end within the chamber above the bottom of said chamber, and a top having a plurality of outlets through it for the discharge of burning gases from the chamber.

8. A burner according to claim 7 wherein the secondary air inlet is located at a point which is spaced from and which is preferably substantially diametrically opposite the supply passage.
